UNITED STATES PATENT OFFICE.

HISASHI SASAKI, OF LOS ANGELES, CALIFORNIA.

AUTOMATIC REFILLING LEAD PENCIL.

Application filed June 25, 1923. Serial No. 647,620.

This invention relates to an improvement in refillable lead pencils, and has for its objects to provide a pencil of this character having means for holding lead refills, for holding a single lead in writing position relative to the casing, means for adjustment of the lead in the writing position, and means for automatically replacing a new lead in the writing position when the worn lead is no longer usable. It is a special design of this invention to provide a lead pencil capable of holding a quantity of lead refills, and having means for automatically feeding a new lead to the writing position.

With the above ends in view the invention resides in the combination and arrangement of parts as more fully set forth in the subjoined detail description, and defined in the claims.

In the drawings, Figure 1 is a side view of my improved automatic pencil. Fig. 2 is an enlarged and longitudinal sectional view of the same. Fig. 3 is a cross-sectional view taken on the line X²—X³, of Fig. 2,

Fig. 4 is a perspective detail view of the hopper for the lead refills. Fig. 5 is a detail view of the tapered cap for the casing. Fig. 6 is a top view of the follower which propels the leads from the casing. Fig. 7

is a side detail view of the follower. Fig. 8 is a longitudinal and sectional view of the casing. Fig. 9 is a detail view of the rotatable actuator for the follower. Fig. 10 is a fragmentary and detail view of the follower

showing the means for releasing the same from engagement with the rotary actuator at the limit of its propelling stroke. Fig. 11 is a similar view of the follower showing the actuating cam in operative position, and

the releasing cam in inoperative position. Fig. 12 is a side view of the non-rotative portion of the lead hopper. Fig. 13 is a cross-sectional view of the hopper showing the inner cams which serve to force the leads

into position in the path of the follower. Fig. 14 is a longitudinal and sectional view of the pencil. Fig. 15 is a longitudinal and sectional view of the hopper casing. Fig. 16 is a perspective view of the hopper casing.

Assuming the invention to be embodied in the form illustrated, my improved pencil consists of a casing 21, provided on its lower end with a tapered cap 22, having screw

threads 23, for connection with the casing. A rotatable cap 24, having a knurled edge

25, is revolvably connected with sleeve 26, screw-connected to casing 21. Within the casing, is mounted a hopper 27, adapted to contain lead refills 28, and having an aperture 29, through which the lead refills may be inserted. The hopper has a chute 30 at the bottom, through which the lead is propelled, the lead extending through aperture 31 in writing. An extension 32, having a bore 33, extends coaxial with chute 30. The hopper has a revolvable casing 34, which is eccentrically disposed relative to chute 30 and extension 32, and concentrically disposed relative to shaft 51, connecting the heads 52 and 53, of the hopper. A follower 35 is adapted to extend within the hopper and to pass through bore 33. A spring 36, coiled around the casing 34, has one end connected to casing 34, and the opposite end connected to the head 53, of the hopper. The shaft 51 has a projecting rib 54 extending longitudinally through the hopper, and adjacent to the axis of the chute and extension 32. The hopper casing 34, has a rib 55 extending longitudinally through the hopper, and serving to force the leads against rib 54 and in alignment with the bore of the chute and in the path of the follower 35. The spring 36 actuates the casing 34, so that the rib 55 serves as a follower for the leads within the magazine of the hopper. The tension of spring 36 serves to prevent the leads from falling from the cap 22 and from the magazine of the hopper.

The follower 35 is provided with an enlarged and tubular portion 37, and a projecting rib 38 which slides between longitudinal guides 39, on the inner wall of casing 21. Cap 24, has an integral and threaded shank 40, extending into the tubular portion 37, of the follower. A spring member 41, fixed to part 37, has a cam 42, projecting inwardly through aperture 43, and engaging with shank 40. The rotation of shank 40 therefore serves to actuate the follower, and thereby impel the lead through cap 22. A spring 44, fixed to part 37, has a cam 45, adapted to engage with a movable cam 46, pivotally mounted on the part 37. Spring 44 has a second cam 47, adapted to slide beneath spring 41. Shank 40 is arranged with its threads decreasing to nil at its extremity 55, so that, as the follower 35 approaches the limit of its lead-impelling movement, cam 42 is disengaged from the threaded

shank 40, and a cam 47 thereupon slides beneath spring 41, to retain cam 42 in its engaged position while the follower 35 is moving to its initial position. Spring 48, 5 interposed between collar 49 on hopper extension 32, and the tubular part 37, of lower 35, actuates the follower to its initial position. As the follower approaches its initial position, the upper extremity 50, of 10 movable cam 46, engages with top cap 24, and the impact thereof against cam 45, is effective to lift spring 44, and disengage cam 47 from spring member 41, thus allowing cam 42 to resume its normal position in engagement with threaded shank 40. When 15 the follower has resumed its initial position, the spring 36, will actuate the tubular element 34, and a lead refill will then be forced against the rib 54, and into alignment with 20 the chute and the bore 33, and in the path of the follower 35. Then, as the knurled cap 24 is rotated, the lead will be impelled through chute 30 and through aperture 31, in cap 22. As the lead is worn away, the 25 cap 24 may be further rotated to force a portion of the lead to extend from the cap member 22.

From the foregoing description and the drawings, it will be readily seen that the 30 device is effective for containing a quantity of lead refills, effective for impelling the leads to writing position as they are worn by use, and effective for automatically feeding a new lead to the writing position, when 35 the worn lead is no longer usable, and that all of these functions are accomplished by the manual rotation of the knurled cap member 24 at the upper extremity of the casing.

The invention includes a magazine hopper 40 for the lead refills, a spring-actuated follower to impel the leads consecutively from the magazine hopper and automatically returnable to its initial position, and a spring-actuated element working within the hopper, 45 and serving to feed the lead refills into the path of the follower and to retain the lead refills in operative position in advance of the impelling follower, and relative to the casing.

50 The bores of the chute and aperture 33, are off-set relative to aperture 31, an infinitesimal amount, effective to retain the lead in writing position and projecting from cap 22.

55 What is claimed is:

1. A lead pencil comprising a tubular casing, a tapered and apertured cap at the lower extremity of the casing, a revoluble cap at the opposite end of the casing, a threaded shank integral with the revoluble cap and having the threads decreasing at the extremity thereof to nil, a lead hopper within the casing, heads forming the ends of the hopper, opposed and co-axial projections 60 extending from the hopper heads and each

having a hollow bore, a magazine casing revolvably mounted between the hopper heads, and disposed in eccentric relation with the tubular extensions, a shaft connecting the hopper heads and arranged eccentric with the tubular extensions, a rib on the shaft arranged longitudinally within the magazine casing and fixed to the shaft, a rib fixed to the magazine casing, and movable relative to the first-named rib, a spring 70 having one extremity fixed to the magazine casing and the opposite end fixed to the lower hopper head, and actuating the magazine casing and its movable rib, a follower slidable within the tubular pencil casing and 75 extending within the hopper and serving to impel the lead from the hopper and into the lower casing aperture, an enlarged tubular portion forming the upper part of the follower, and sliding over the threaded 80 shank, a spring-actuated cam mounted on the tubular portion of the follower and engaging with the threaded shank and disengaging therefrom at the extremity thereof, another spring-actuated cam angularly 85 disposed relative to the first-named spring-actuated cam, and operative to retain the said first-named cam in its disengaged position, a tiltable cam mounted on the follower and adjacent to the last-named spring-actuated cam, an arm on the tiltable cam adapted 90 to engage with the top cap to release the last-named spring-actuated cam as the follower approaches its initial position, and a coiled spring interposed between the hopper and the tubular part of the follower and operative to force the follower to its initial position when the cam is disengaged 95 from the threaded shank.

2. A lead pencil comprising a tubular casing, a tapered cap at the lower extremity thereof and having an aperture, a knurled cap at the opposite extremity of the casing and revolvably mounted thereon, a threaded shank depending from the knurled cap, a 100 hopper within the casing adapted to contain the lead refills, a follower within the casing and having one end sliding in the hopper, a spring-actuated cam on the follower and in engagement with the threaded shank, and means for releasing the spring-actuated cam from engagement with the shank, as the follower approaches the limit 105 of its sliding movement within the hopper.

3. A lead pencil comprising a tubular casing, a tapered cap at the lower extremity thereof and having an aperture, a knurled cap at the opposite extremity of the casing, a threaded shank depending from the 110 knurled cap, a hopper within the casing and having a chute terminating adjacent to the aperture in the tapered cap, and having a hollow guide member extending from the 115 opposite end of the hopper and with its bore arranged co-axial with the chute, the 120

hopper having its walls contracted to form a groove in alignment with the hollow guide member and the chute, a follower slidably mounted in the casing and extending through the guide member and within the hopper, a spring-actuated cam on the follower in engagement with the threaded shank, and means for releasing the cam as the follower approaches the limit of its 10 sliding movement within the hopper.

4. A lead pencil comprising a tubular casing, a tapered cap at the lower extremity thereof and having an aperture, a knurled cap at the opposite extremity of the casing, a threaded shank depending from the knurled cap, a hopper within the casing, a chute and a guide member extending in opposed relation from the hopper and each having a hollow bore, a coiled spring encircling the hopper and maintaining the hopper in eccentric relation to the casing, and with the bore of the chute in eccentric relation with the aperture in the tapered cap, a follower slidably mounted in the casing and extending through the guide member and within the hopper, a cam on the follower and in engagement with the threaded shank, guide members on the inner wall of the casing, a rib on the follower and sliding between said guide members, means for releasing the cam as the follower approaches the limit of its sliding movement within the hopper, and means for retracting the follower to its initial position when its actuating cam is released.

5. A lead pencil comprising a tubular casing, a tapered and apertured cap at the lower extremity of the casing, a revolvably mounted and knurled cap at the opposite extremity of the casing, a threaded shank integral with the revolvble cap and extending within the casing, a lead hopper extending within the casing, a hollow chute and hollow guide member projecting in opposed relation from the hopper, a follower sliding in the guide member and extending within the hopper, means for preventing rotation of the follower, a spring-actuated cam on the follower and in engagement with the threaded shank, means for releasing the cam as the follower approaches the limit of its sliding movement, means for retracting the follower to its initial position when the spring-actuated cam is released, and means for releasing the cam-releasing means as the follower approaches its initial position.

6. A lead pencil comprising a tubular casing including a tapered cap having an aperture, a revolvble cap at the opposite end of the casing, a threaded shank integral with the revolvble cap, a lead hopper within the casing, opposed and co-axial projections extending from the hopper and each having a hollow bore, the projections being arranged eccentric with the body of the hopper, a spring serving to maintain the hopper in eccentric relation with the casing, a follower slidably mounted in the casing and extending within the hopper and serving to impel a lead from the hopper and into the casing aperture, an enlarged tubular portion on the follower and sliding over the threaded shank, a spring-actuated cam mounted on the tubular portion of the follower and engaging with the threaded shank, the threaded portion of the shank decreasing to disengage the cam at the extremity of the shank, another spring-actuated cam angularly disposed relative to the first-named spring-actuated cam, and operative to retain the cam in its disengaged position, a tiltable cam pivotally mounted on the follower and adjacent to the last-named spring-actuated cam, an arm on the tiltable cam, and engaging with the revolvble head to release the last-named spring-actuated cam, and a coiled spring interposed between the hopper and the enlarged portion of the follower and operative to force the follower to its initial position when the cam is disengaged from said threaded shank.

7. In an automatic lead pencil, the combination with a casing having an aperture in one end thereof, of a magazine hopper mounted within the casing and having a lead ejecting aperture normally in off-set position relative to the casing aperture, a follower arranged to impel the leads from the magazine hopper, a manually operated screw mechanism to actuate the follower with its impelling movement, a spring arranged to return the follower to its initial position, a rib element arranged within the hopper to feed the lead refills into the path of the follower, and a spring to actuate the hopper to maintain the said rib element in its working position, and to maintain the hopper aperture in off-set relation with the casing aperture.

In testimony whereof, I hereunto affix my 110 signature.

HISASHI SASAKI.
